UNITED STATES PATENT OFFICE.

WILLARD G. PHILLIPS, OF LOS ANGELES, CALIFORNIA, ASSIGNOR TO CLAUDE A. COUNTS, OF LOS ANGELES, CALIFORNIA.

ADJUSTABLE ROPE-TIE.

1,300,006.

Specification of Letters Patent.

Patented Apr. 8, 1919.

Application filed December 16, 1918. Serial No. 266,985.

To all whom it may concern:

Be it known that I, WILLARD G. PHILLIPS, a citizen of the United States, residing at Los Angeles, in the county of Los Angeles and State of California, have invented new and useful Improvements in Adjustable Rope-Ties, of which the following is a specification.

My invention relates to a tying device for use with ropes, cords and the like.

An object of my invention is to provide a simple, convenient and secure tying device for use with ropes, cords and the like employed in tying bundles.

Another object is to provide an inexpensive automatic, adjustable tying device for general use with ropes and cords.

With these and other objects in view, my invention consists in the construction, combination and arrangement of parts herein-after described and claimed.

In the accompanying drawings which form a part of this specification,

Figure 1 is a view in perspective of a rope tie embodying the principles of my invention, showing the method of attaching the rope ends.

Fig. 2 is a top plan view of the rope tie shown in Fig. 1.

Fig. 3 is a central longitudinal section of the rope tie shown in Fig. 2.

Fig. 4 is an end view of the rope tie shown in Fig. 3 as seen from the right hand end.

The parts of the tie, as shown in the drawings, are made of sheet metal. The tie consists of two parts: a fixed plate 10 and a movable plate 11 adapted to slide on the fixed plate. The movable plate is provided with two hinged members: a locking member 13 and a clamping member 14. The fixed plate is formed of a piece of rectangular sheet metal bent longitudinally into a channel 15. Its sides 16 and 17 are then bent outwardly so as to form longitudinal flanges 18 and 19, these flanges being in transverse alinement with each other. Tongues 20 and 21 are stamped out of the channel section 15 near its ends and are bent outwardly and returned against the plate to form rounded tie bars for the attachment of the rope ends. The flanges 18 and 19 serve as guide bars for the movable plate 11 and have a series of notches 22 filed in

The sliding plate 11 is formed of a similar but smaller rectangular piece of sheet metal placed crosswise of the fixed plate so as to rest upon the guide bars 18 and 19. Its ends are bent downwardly outside the guide bars and returned under them, thus forming guideways 23 and 24 and holding the movable plate in slidable contact with the fixed plate.

The clamping member 14 is formed of an irregular piece of sheet metal and has a pivot shaft 14' fixed to one end so that its ends 25 and 26 project laterally and turn in bearing lugs 27 and 28 punched out of the movable plate and bent at right angles to its outer face. The opposite end of the clamping member is narrowed and rounded and bent under to form a clamping tongue 29 which co-operates with the tie bar 21 to grip the rope. The gripping surface 29' of the clamping tongue 29 is milled or furrowed to increase its frictional effect. A tongue 30 is punched out of the clamping member and bent outwardly to serve as a trigger by which to lift the clamping member out of engagement with the rope when it is to be released.

The locking member 13 is formed of an irregular piece of sheet metal with upturned lugs 33 and 34 at its sides through which a pivot shaft 35 is fixed. The projecting ends of this shaft turn in lugs 36 and 37 punched out of the movable plate and bent upwardly to serve as bearing lugs. Downwardly extending catch teeth 38' are formed on the inner end of the locking member. These, in their locking position, project downwardly through the punching holes 36' and 37' out of which the lugs 36 and 37 were punched, and engage the teeth 22 of the guide bars 18 and 19 to hold the movable plate in locked relation to the fixed plate. The outer end of the locking member is narrowed and rounded into a trigger 38 for manipulation in unlocking and locking the movable plate.

Operation: One end of the rope 39 is passed through the eye 20' formed by punching out the tongue 20 and is securely tied to one end of the fixed plate. It is then passed around a bundle or the like, and is pulled through the eye 21' formed by punching tongue 21. It is then pulled tight and the clamping member is pressed against it by manipulation of the trigger 30. It is evi-

dent that as the loose end of the rope 40 is released the backward pull of the rope against the clamping member 14 tends to pull it inwardly against the fixed plate and tighten its grip on the rope so that the rope is securely held from slipping. When it is desired to release the rope, the free end 40 is pulled as in tightening and simultaneously the trigger 30 is manipulated to lift the clamping member 14 from engagement with the rope, whereupon the rope may be easily withdrawn. When it is desired to use a thicker rope than the one shown in the illustration, the trigger 38 of the clamping member is pulled outwardly, thus disengaging the ratchet teeth 38' from the ratchet 22 and allowing the locking plate to be shifted so as to enlarge the opening between the clamping member 14 and the tie bar 21. The trigger is then forced inwardly toward the fixed plate bringing the ratchet teeth into engagement with the ratchet and locking the plates in the new position.

While I have shown the preferred construction of my adjustable rope tie as now known to me, it will be understood that various changes in construction and arrangement of

parts may be made by those skilled in the art without departing from the spirit of my invention as claimed.

30

I claim:

1. An adjustable rope tie comprising a fixed plate provided with tie bars and notched guide bars; a movable plate slidably mounted on said fixed plate; a clamping member pivotally mounted on said movable plate in coöperative relation with one of said tie bars; and a locking member pivotally mounted on said movable plate, said locking member being provided with catch teeth 40 adapted to engage with the notches in said guide bars whereby said movable plate is held in locked relation to said fixed plate.

2. An adjustable rope tie comprising a fixed plate provided with tie bars and notched guide bars; a movable plate slidably mounted on said fixed plate; a clamping member pivotally mounted on said movable plate in coöperative relation with one of said tie bars; and means for holding said movable plate in locked relation to the fixed plate.

In testimony whereof I have signed my name to this specification.

W. G. PHILLIPS.
